PRESSURE CASTING APPARATUS.

1,039,234.

Specification of Letters Patent. Patented Sept. 24, 1912.

Application filed July 18, 1911. Serial No. 895,105.

To all whom it may concern:

Be it known that we, SAMUEL PRICE WETHERILL, Jr., and ALBERT W. MORRIS, citizens of the United States, both residing at Philadelphia, county of Philadelphia, State of Pennsylvania, have invented certain new and useful Improvements in Pressure Casting Apparatus; and we do hereby declare the following to be a full, clear, and exact description of the invention, such as will enable others skilled in the art to which it appertains to make and use the same.

This invention contemplates certain improvements in the art of pressure casting, which are designed to contribute to the excellence and uniformity of the product through the employment of an improved cycle of operation and the attainment of a greater measure of uniformity in the recurrence of that cycle.

The apparatus herein described, and illustrated in the accompanying drawing, is intended for use in connection with a pressure casting furnace of the type in which molten metal in a closed vessel is raised or otherwise transferred into a mold, through a nozzle or up-take, by the admission of air under pressure to the interior of the closed vessel. Heretofore, the operation of admitting air under pressure into the receptacle containing the molten metal has been performed by the direct manipulation of valves by the operator and has required considerable skill to effect the required cycle, for the molten metal must be quietly raised or transferred by low pressure into the mold until the mold is filled and must be held under compression therein by high pressure until it sets. The admission of the air under pressure has been attended by serious difficulties, which occasioned many accidents and failures. Thus, when through the lack of skill or the inadvertence of the operator, the air is brought abruptly, in large quantity, into contact with the hot metal to raise it into the mold, the resulting expansion occurs with a violence little short of an explosion, and when this occurs, the metal spouts into the mold in a divided state and is chilled into an imperfect casting before any subsequent action by the operator can rectify the error. Furthermore, an initial disturbance of the metal by the resilient

air sets up an oscillation in the molten metal, the tendency of which is to draw out a part of the metal that has been raised into the mold and permit the remainder to chill with imperfections. The operator, however skillful, can but imperfectly manipulate the usual supply valve in the endeavor to avoid these difficulties and to reproduce successively the cycle of operations which will produce the best results, and this is not surprising when we consider that the several operations making up a complete cycle have to take place in a very short space of time owing to the quick chilling of the metal. In order to produce a homogeneous casting, moreover, a high pressure should be applied at the instant when the metal has completely filled the mold and should be continued while the metal sets therein, and, when this has been attempted, the difficulties incident to the control of a high pressure supply of air (and especially the avoidance of an abrupt initial admission of air into the furnace) have added to the unfavorable chances of producing good castings. We have eliminated these embarrassments, first, by providing separate sources of air under pressure for the low pressure and for the high pressure, and by providing separate co-acting valves therefor, which, however, are isolated from one another in the sense that detrimental leakage from the one to the other is avoided; and, secondly, by providing a mechanical device for operating these valves which is adaptable to the performance of any cycle of operation that may be required and which will repeat that cycle with precision.

Apparatus embodying the subject matter of the invention is illustrated in the accompanying drawings, in which—

Figure 1 is a front view, in elevation, of a combined low pressure compressor and valve-operating device to be used in connection with a pressure casting furnace. Fig. 2 is a right-hand side view, in elevation, of the apparatus shown in Fig. 1. Fig. 3 is a detail of the clutch actuating cam. Figs. 4, 5 and 6, are sectional views of the valve housing, forming a part of the apparatus illustrated in Figs. 1 and 2, and show the three principal positions of the controlling valve for the low pressure and high pressure

air supplies. Fig. 7 is a left-hand side view, in elevation, of the apparatus shown in Fig. 1.

Similar letters of reference indicate similar parts throughout the several views.

Referring to the drawings, A indicates a base casting upon which the machine is assembled. A crank shaft B is journaled in bearings on the casting A and is provided with a worm gear b. A driving shaft C is journaled in bearings on the casting A and carries a worm c, which engages with the worm gear b to drive the crank shaft B. The extended end of the driving shaft C is reduced in diameter and is supported in a floor bearing c'', and a driving pulley D is loosely mounted on this reduced portion between the shoulder formed on the shaft C and the inner face of bearing c''.

20 A cam shaft E is mounted in bearings in the base casting A parallel with the crank shaft B and is geared to run synchronously with the crank shaft B through the medium of a spur gear b', fast on crank shaft B, and a like spur gear e', fast on the cam shaft E.

A cam wheel F is mounted fast on one end of the cam shaft E and has a cam groove f in its outer face, which is designed to direct the movement of a clutch actuator G by the engagement with said groove of a pin g, mounted to reciprocate in the actuator G and normally spring-pressed into engagement with said groove. The clutch actuator G has the form of a yoke and engages an annular groove in a clutch member c', which is splined to the driving shaft C and which is designed to be moved into and out of engagement with a complementary clutch

40 member d on the inner face of the driving pulley D, to respectively connect and disconnect the continuously running driving pulley D and the driving shaft C. The greater part of the groove f in cam wheel

45 F is concentric with the cam shaft E and when the pin g on the clutch actuator G is engaged in this part, the clutch members c' and d are interlocked, the driving pulley D drives the driving shaft C and the machine 50 is in operation; but, when a deflection f' at the end of this concentric part of the groove f moves the pin g, the clutch members c' and d are separated by the movement of the clutch actuator G and the machine stops

55 automatically. It will be seen that this automatic stopping of the machine must occur at the end of each revolution of the crank and cam shafts B and E. The machine is started upon a subsequent revolution (after it has been stopped through the engagement of pin g with the deflection f' in groove f) by a hand lever g', pivoted on the clutch actuator G, and connected with the pin g, serving to withdraw the pin g en-

70 at right angles thereto engages the clutch member c' and d. The hand lever g' is held in this position, until the advance of the deflection f' in groove f admits of the pin g being projected by its spring into the concentric part of the groove f. A cam-holding plate H is mounted fast on the opposite end of cam-shaft E and is provided with a circular series of equidistant perforations. Two cams h and h', of greater diameter 75 than the cam-holding plate H, are each recessed to fit the periphery of and extend over the cam-holding plate H to abut one another when placed upon opposite sides of said plate, and each of these cams is provided with a circular series of perforations 80 exactly registering with those in the cam-holding plate H, in such manner that they may be bolted to that plate in various positions relative to one another and to that 85 plate. The cams h and h' have like low peripheral arcs corresponding to the lowest position to be assumed by the member to be actuated by them, and the cam h has a high peripheral arc corresponding to an intermediate position of that member, while the high peripheral arc of the cam h' corresponds to the highest position to which the actuated member is to be moved.

An upright cylinder I is mounted upon 95 the base casting A, and a piston i is actuated in said cylinder by the crank shaft B through connecting rod i'. The crank of crank-shaft B is timed to be at its lowest position (and the piston i, therefore, at the lower end of 100 its stroke) when the machine is automatically stopped, and the piston i consequently makes one up and one down stroke during each cycle of the machine.

A valve chamber J is mounted upon the 105 top of the cylinder I and contains reciprocating valves whose common stem j is connected to one arm of a bell crank K. The other arm of bell crank K is connected to a reciprocating rod k having, upon its lower 110 end, a roller k' which traverses the cams h and h' on cam shaft E. Through this last described mechanism, the cams h and h' effect the movement of the valve in valve chamber J. The only passage to or from 115 cylinder I, is port L (see Fig. 4) leading into the valve chamber J. The valve stem j carries all of the valves, one of which, (namely, a valve M) in the first position of the valves shown in Fig. 4, opens communication between the port L and a relief port N to atmosphere, and, in this position of the valve stem j, the port L is also in communication with a chamber O from which a pipe o leads to the closed molten metal 125 receptacle of the pressure casting furnace. In this first position of the valves, a second valve P closes communication between the chamber O and a annular port p, which is connected by longitudinal passage p' with 130

second annular port p'' , while a third valve Q closes communication between the port p'' and a chamber R , to which chamber air under high pressure is led by a pipe r from a suitable source. Should air under high pressure leak past valve Q , in this first position, it is exhausted from port p'' through relief port g to atmosphere, and not allowed to leak past valve P into chamber O from which it would flow to the furnace. In other words the supply of air at high pressure is cut off at two points by the valves P and Q and the leakage relief port g is opened between these points. When the valve stem j is moved to its second or intermediate position (see Fig. 5) by cam h , the relief port N is closed by valve M , and the other established communications are not effected. The piston i is rising in cylinder I during this part of the cycle and the air displaced thereby passes through port L to chamber O and thence through pipe o to the furnace, producing a low pressure therein to raise the molten metal into the mold. When the valves are moved to their third position, (see Fig. 6) by cam h' , the valve M closes communication between the port L and the chamber O , and opens communication between port L and relief ports S leading to the surrounding atmosphere, the valve P closes the relief port g and opens communication from annular port p to chamber O , and the valve Q opens communication between chamber R and annular port p'' , admitting air under high pressure from chamber R to port p'' , which then passes through passage p' to port p and chamber O and thence through pipe o to the furnace. The valves are brought back to their first position by the fall of the roller h' to the low peripheral arcs of the cams h and h' .

The machine is belted to run uniformly at a suitable speed.

In adjusting the machine for a given cycle a point in the upward stroke of the piston i is chosen at which the piston travel is best adapted for the application of low pressure to the furnace. If it is desired to apply the low pressure air gradually by an increasing piston speed from zero, the cam h is set to raise the roller h' immediately after the start of the machine and while the crank of crank-shaft B is on or near its lower center, but, if a quicker application of the low pressure is desired, the cam h may be set for later action, at or nearer the time when the crank reached a horizontal position, in which case the air displaced by the piston i prior to the action of the cam h will pass out of the relief port N . By a still later set of the cam h , the gradually lessening displacement of the piston i as the crank passes to its upper center may be utilized to good effect in some instances. The cam h is set to raise the roller h' and move the valves

to their third position when the low pressure has been applied for a sufficiently long period of time, and, owing to the positioning of the valves M , P , and Q relatively to the passages they are intended to open or close, this movement to the third position shuts off the low pressure supply of air from cylinder I to the furnace at the exact instant that the high pressure from chamber R is admitted to the furnace. The egress and ingress of air from and to the cylinder I , due to the further movement of the piston i after the valves have been moved to their third position, take place freely through the relief ports S . The high pressure supply of air to the furnace continues throughout the travel of the high peripheral arc of the cam h' under roller h' and is always of the same duration relatively to the speed of the machine, there being no objection to its continuance throughout this period as the casting is not affected by pressure after it has sufficiently set. As soon as the roller h' drops from the cam h' to its initial position bringing the valves from the third to the first position again, the residual pressure in the furnace is exhausted through chamber O and port N , and the machine is automatically stopped by the operation of the stop mechanism hereinbefore described when a complete revolution of the crank and cam shafts has taken place. The mold may then be opened and the finished casting removed and the mold closed again. After this has been done, the operator starts a second cycle by operating the hand lever g' to engage the clutch members c' and d , the pin g again engaging the groove f when its concentric part is reached. In this way, successive cycles may be started at the will of the operator and carried out with precision, all being identical in every respect.

It is essential that the high pressure air supply shall not leak from the chamber R to the chamber O before or during the application of the low pressure to the furnace, or in other words, during the first and second positions of the valves, as it would build up high pressure in the furnace at a time when the metal did not entirely fill the mold and defeat the purpose of the invention, and this building-up is provided against by interposing the space between valves P and Q , open to the atmosphere through relief port g during the two positions of the valves named, so as to exhaust any such leakage.

Having thus described our invention what we claim is:

1. In pressure casting apparatus of the character described, the combination with the chamber containing the molten metal, of a valve for admitting compressed air thereto, and automatic power driven mechanism operatively connected with said valve

- to effect successive similar cycles of movement of said valve; substantially as described.
2. In pressure casting apparatus of the character described, the combination with the chamber containing the molten metal, of a valve for admitting compressed air thereto and automatic power driven mechanism operatively connected with said valve to effect a predetermined cycle of operation of said valve, said mechanism being adapted to be manually started and automatically stopped at the expiration of said cycle; substantially as described.
3. In pressure casting apparatus of the character described, the combination with the chamber containing the molten metal, of separate sources of air under low pressure and high pressure respectively, and means whereby communication may be established between said chamber and the source of air under low pressure, and subsequently between said chamber and the source of air under high pressure; substantially as described.
4. In pressure casting apparatus of the character described, the combination with the chamber containing the molten metal, of separate sources of air under low pressure and high pressure, respectively, and cooperating valves associated to first establish communication between said chamber and the source of air under low pressure, and to then cut off said communication and simultaneously establish communication between said chamber and the source of air under high pressure; substantially as described.
5. In pressure casting apparatus of the character described, the combination with the chamber containing the molten metal, of a cylinder, a piston therein, means for reciprocating said piston, and a valve actuated by said means to effect communication between said chamber and said cylinder during a certain portion of the travel of said piston, and to effect communication between said cylinder and the atmosphere throughout the remainder of the cycle of said piston; substantially as described.
6. In pressure casting furnace of the character described, the combination with the chamber containing the molten metal, of a cylinder, a piston therein, means for reciprocating said piston, and a valve actuated thereto to effect communication between said chamber and said cylinder during any desired portion of the travel of said piston and to effect communication between said cylinder and the atmosphere throughout the remainder of the cycle of said piston; substantially as described.
7. In pressure casting apparatus of the character described, the combination with the chamber containing the molten metal, of a cylinder, a piston therein, manually startable and automatically stopping mechanism operatively connected to said piston to reciprocate the same, and a valve actuated by said mechanism and adjustably connected thereto to effect communication between said chamber and said cylinder during any desired portion of the travel of said piston, to effect communication between said cylinder and the atmosphere throughout the remainder of the cycle of said piston, and to exhaust said chamber to the atmosphere while said mechanism is at rest; substantially as described.
8. In pressure casting apparatus of the character described, the combination with the chamber containing the molten metal, of a source of air under high pressure, and a valve adapted to effect communication between said chamber and said source of air under pressure when in one position, and in another position to close said communication at two points and open a relief port to atmosphere to intercept leakage from said source of air at high pressure into said chamber; substantially as described.
9. In pressure casting apparatus of the character described, the combination with the chamber containing the molten metal, of a source of air under high pressure, a second source of air under low pressure, and a valve adapted to effect asynchronous communications between said chamber and each of said sources of air under pressure, said valve being designed to close the conduit from said source of air at high pressure at two points and open a relief port to atmosphere to intercept leakage from said source of air at high pressure into said chamber or into said source of air at low pressure; substantially as described.
10. In pressure casting apparatus of the character described, the combination with the chamber containing the molten metal, of a conduit leading thereto, a source of air under high pressure supplying said conduit, and a valve governing the passage of the high pressure air through the conduit at two points and likewise governing a leakage relief port intermediate of said points; substantially as described.
11. In pressure casting apparatus of the character described, the combination with the chamber containing the molten metal, of a source of air under high pressure, a cylinder, a piston therein, means for reciprocating said piston, and a valve operatively connected with said piston and arranged to afford communication at different times between said chamber and said cylinder and between said chamber and said source of air under high pressure; substantially as described.
12. In pressure casting apparatus of the character described, the combination with

the chamber containing the molten metal, of a source of air under high pressure, a cylinder, a piston therein, manually startable and automatically stopping mechanism 5 operatively connected to said piston to reciprocate the same, a valve actuated by said mechanism and adjustably connected thereto, to afford communication between said furnace and said cylinder during any 10 desired portion of the travel of said piston, to afford communication between said cylinder and the atmosphere throughout the remainder of the cycle of said piston, to afford communication between said furnace 15 and said source of air under high pressure

during any desired part of said remainder of the cycle of said piston, to close said last named communication at two points and open a leakage relief port therebetween, and to exhaust said furnace to the atmosphere 20 while said mechanism is at rest; substantially as described.

In testimony whereof we affix our signatures, in presence of two witnesses.
